CAN OPENER

Gayne Chun, Honolulu, Territory of Hawaii
Application March 4, 1954, Serial No. 414,144

1 Claim. (Cl. 30—6.1)

The present invention relates to a can opener and, more particularly, to a new and improved can opening device formed to pierce a preliminary vent in the top of the can and to shield the vent before opening the can.

Although can openers and the like embodying the principles of the present invention are devices of general utility, they enjoy particularly advantageous use in opening cans containing effervescent liquids and semi-liquids or semi-solid liquids and liquids or semi-solid liquids containing gases and the like, such as carbonated beverages and the like.

When opening cans containing materials such as those immediately hereinabove described, with can openers commonly used and made in accordance with prior art disclosures, there frequently resulted a spraying or splashing of persons and articles within a relatively large area about the can. This undesirable spraying was caused from the escape of wet gases and the like through the hole cut or punched in the can without shielding the hole.

In accordance with the principles of the present invention, however, a can opener or the like may be provided with means to shield the first punched hole, thereby protecting people and articles in the area surrounding the can from spray from the can.

It is, therefore, an important object of the present invention to provide a new and improved can opener so constructed and arranged as to pierce a preliminary venting hole in the can and to shield the venting hole.

Another distinctive advantage of can openers and the like embodying the principles of the present invention lies in the construction feature whereby, in a single movement of the can opener, the can is opened as by cutting a relatively large aperture in a surface thereof, and an auxiliary air vent aperture is punched or cut or the like into the same surface of the can. This advantage and the means for providing the same result in time and energy savings of considerable value since can opening, as the same was conducted with prior art can openers, required dual actuation of the can opener as by punching one hole at one edge of the can and then removing the can opener to the other side and punching a second hole therein, thereby extending twice as much energy and twice as much time as would be required to effect a single movement of the can opener.

It is, therefore, another important object of the present invention to provide a new and improved can opener having means thereon to cut or punch or the like a principal can opening aperture in the can and means thereon to punch an auxiliary venting aperture in the can in a single motion of the can opener.

Still another object of the present invention is to provide a new and improved can opening device operable in a single motion thereof to successively cut a gas escape vent aperture therein, cut a principal can opening aperture therein, and cut a secondary venting aperture in said can substantially diametrically opposite to the principal opening aperture.

Still another object of the present invention is to pro-

2

vide a new and improved can opener wherein a handle or body portion has a cutting blade formed integrally therewith and a vent punching blade formed integrally with the first blade and extending transversely therefrom to intersect the can to be opened prior to intersection of the principal cutting blade with the can, thereby to cut a principal venting aperture in the can and to shield the venting aperture with the principal cutting blade.

Still other objects, features and advantages of the present invention will become readily apparent from the following detailed description of the principles of the present invention and preferred embodiments thereof, from the claim, and from the drawings, in which preferred embodiments of the present invention are illustrated and fully and completely disclosed by every detail shown on the drawings, in which like reference numerals refer to like parts, and in which:

Figure 1 is an elevational view of a can opener and the like embodying the principles of the present invention;

Figure 2 is a cutting blade end elevational view of the can opener of Figure 1;

Figure 3 is a sectional view through the principal cutting blade and is taken substantially along the line III—III of Figure 2;

Figure 4 illustrates the embodiment of Figure 1 in association with a can or the like for opening the same and shows the can opener in a post-cutting position by phantom lines; and

Figure 5 is an isometric view of another embodiment 30 of the invention.

Can opening, and particularly opening cans containing such effervescent fluids as beer and the like, and, in accordance with the principles of the present invention, is a multistep operation which may be conducted in a single movement of the can opener constructed in accordance with the principles of the present invention. One of the important steps in the can opening operation includes piercing, puncturing or cutting an initial venting aperture in the can top or lid or cover and shielding the aperture or orifice so made therein to prevent undesirable spraying and the like from the can, due to the pressurized wet gases within the can and the release of the same. By shielding the initial venting aperture, any spray or foaming over or the like is restricted to relatively easy control and undamaging flow in a most desirable manner.

By way of example, and not by way of any limitation, there is illustrated in Figures 1 through 4 a can opener which embodies the principles of the present invention and is operable to punch a preliminary or initial venting aperture in a can top and to shield the same prior to cutting a principal can opening aperture in a can cover, and to cut the principal can opening aperture in the can top or cover. To this end, the can opener 10 of Figures 1 through 4 is of the type which may be formed in a punching or stamping operation from any substantially rigid material such as a metallic material or the like, and is formed with a body or handle member 11 on one end of which there is a principal or primary cutting blade 12 and a vent piercing blade 13. The blade 12 is the principal can opening aperture blade, and when formed integrally with the handle or body member 11, is bent to be positioned at an angle to the plane of the body or handle member 11 and substantially along a line which is substantially transverse to the longitudinal axis or center line of the handle or body member 11.

The details of the contouring configuration of the principal aperture cutting blade 12, as shown in the drawings, is such that it is substantially spherically triangular or the like. That is, the blade 12 is formed with a pair of cutting edges 14 and 15 which arcuately extend from a center line point or vertex 16 to the sides of the body or handle member 11 and merge therewith. The

edges 14 and 15 are formed by tapering the side faces 17 and 18, respectively, outwardly thereto from the outer convexly curved face or surface 19 of the blade 12. The cutting edges 14 and 15 form the outer limits of an inner or concave curved surface 20. The curvature of the surfaces 19 and 20, which surfaces are substantially parallel, is such that during a can opening operation the cutting tip or point 16 will be the first portion of the cutting blade 12 to contact the can top.

The concave curvature of the under surface or inner surface 20 of the blade 12 is also formed to provide improved shielding effects against any effervescence from the venting aperture cut by the piercing or punching blade 13. The initial vent cutting blade 13 is punched or the like from a portion of the blade structure for the blade 12 or is a separate member secured thereto and specifically to the inner concave face 20 extending in a direction of the center of curvature for the spherically triangular inner face 20 on the blade 12.

The blade 13 is effective to break the seal in the can and to be the first blade to contact the can and cut or pierce or punch a venting aperture therein. The blade is preferably formed with an angular head having a centered cutting vertex 21 and angularly disposed faces 22 and 23, each of which has a cutting edge 24 and 25, respectively. Further, the effervescence vent cutting blade 13 is preferably disposed at an acute angle to a plane tangent to the principal cutting blade 12 at the position of junction between the blades 12 and 13, and the piercing blade 13 is preferably pointed in a forward direction as toward the point 16 on the principal cutting blade 12. This disposition of the seal breaking or effervescence vent punching blade 13 with respect to the main cutting blade 12 results in an important feature of the present invention. By this arrangement, can opening with the can opener in accordance with the procedure described in connection with the illustration of Figure 4, the effervescence or the like aperture punched in the can lid or top or cover by the blade 13 lies below the solid portion of the concave face 20 of the blade 12 since the aperture cut by the blade 13 is substantially triangular and pointed in the direction of the cutting tip 16 of the blade 12. Thus, by this arrangement, the venting aperture is shieldably covered by the blade 12 and thus prevents undesirable spray and the like from the contents of the can from uncontrollably leaving the can.

The can opener 10 is also provided with a hook like fulcrum or pivot member 26 which may also be punched from the strip of elongated material forming the can opener, and, in the form shown, is preferably punched with the punching of the effervescence vent blade 13. That is, when the handle or body member 11 and the blade 12, along with the blade 13, are formed from a single elongated strip of substantially rigid material by such an operation as a punch press operation or the like, the pivot or fulcrum hook or the like 26 which is formed to hook onto the bead of the can to be opened for pivoting the can opener thereabout, may also be punched in that same operation. When so punched, the fulcrum member 26 is preferably configurated as shown on Figures 1, 2 and 4 to extend from the body or handle member 11 outwardly from the side of the handle member 11 which is substantially the same side as the concave face side of the cutting blade 12, and is adjacent to the transverse line of bend for the blade 12. The fulcrum member 26 is substantially hook shaped and, when punched together with the vent punching blade 13, is provided with a forked tip 27.

The hook or fulcrum member 26 together with a transverse indentation 28 providing a seating recess opposing the hook 26 at the junction shoulder between the blade 12 and body member 11, are properly adapted to engage the bead at the top rim edge of the can which is to be opened to guide the opener 10 pivotally thereabout.

As will be observed from Figure 4, wherein a can 30

having a top 31 joined to the substantially cylindrical side walls thereof along a bead 32 and the can opener 10 are illustrated in solid lines, the can opener 10 is in upright position for initiating opening of the can in accordance with the principles of the present invention. The fulcrum member 26 is hooked over the bead 32 which rests in the indented shoulder 28, so that the vent piercing blade 13 contacts the top 31 of the can at its tip 21.

Pivoting the can opener about the bead 32 downward toward the can top 31 causes the venting blade 13 to pierce through the top of the can and cut or punch a venting orifice therein which will be shielded by the principal can opening aperture cutting blade 12.

When the differential internal and external pressures of the can have been neutralized through the aperture cut by the piercing blade 13, continued downward movement of the blade 12 brings the point 16 thereof into cutting engagement with the top of the can, and thereafter still further continued movement will cause the cutting edges

20 14 and 15 of the blade 12 to cut a pouring aperture in the top 31 of the can. The portion of the top which is punched out by the blade 12 will be bent downwardly into the can by the blade 12 as it moves into the can. This downward movement of the blade 12 and handle or

25 body 11 is continued substantially until the handle or body member 11 approaches close to the can top on bead. The limit of movement is such that the blade 12 and the piercing blade 13 are stopped prior to engagement of the piercing blade 13 with the side wall of the can.

30 This limit is provided by positioning the cutting blade 12 and piercing blade 13 with respect to the handle or body member 11 such that the cutting edge 21 of the piercing blade 13 lies behind a plane perpendicular to the general plane of the handle or body member 11 and includes the pivot axis.

The limited movement of the can opener 10 forming this embodiment of the present invention is further provided by stop means on the handle or body member 11 for engaging the top 31 or bead 32 of the can. One form 40 of particularly advantageous stop means also forms a second vent cutting or piercing means which forms a part of the present invention. This second vent or cutting means is arranged so as to permit and provide for a venting aperture in the can top substantially diametrically opposite to the principal can opening aperture in the can whereby a pouring of the contents of the can from the can may be effected smoothly and evenly and without air pressure locking of the contents of the can.

45 It will be understood, of course, that prior to the present invention proper opening and venting of the can required double operation of the can opener to produce both a pouring aperture and a venting aperture. Can openers embodying the principles of the present invention are operable to cut both of those apertures in a single movement of the can opener pivoting the same about the bead on the can.

A preferred form of venting means and stop means is illustrated in Figures 1 and 4, wherein there is shown a multiple arm or lever like member 35 pivotally secured 60 to the body or handle section 11 of the can opener 10, as by a pivot rivet 36 or the like. The member 35 is positioned adjacent to the under surface of the handle member 11, which surface corresponds to the outer surface 19 of the blade 12, to pivot in a plane parallel therewith, and may be formed from the same material or substantially the same material as the material from which the remainder of the can opener 10 is formed and may be formed in a stamping or punching operation. Further, the pivot rivet or the like 36 is disposed preferably toward the extremity of the handle portion 11 of the can opener, as at 37.

The auxiliary vent punch member 35 is preferably provided with a pair of arms 38 and 39, or more arms if so desired, which arms are of unequal length having down-turned end portions 40 and 41, respectively, which are also

of unequal length, and which terminate in punch blades or the like 42 and 43, respectively.

In this preferred embodiment of the present invention, the downturned end portion 40 carrying the punch blade tip 42 is shorter than the portion 41 and is the terminal portion of the arm 38 which is preferably shorter than the arm 39. The longer downturned portion 41 carrying the punch blade 43 is preferably provided with a shoulder or the like 44—44 adjacent to the punch blade 43.

When opening a can or the like with this can opener embodying the principles of the present invention, the relative diameter of the can is first determined thereby to select the auxiliary vent punch carrying arm which terminates at a proper distance from the principal cutting blade 12 for proper venting of the can. As it is illustrated in Figure 4, by phantom lines, for the ordinary can containing such effervescent fluids as beer and the like the shorter arm 38 is the proper stop and auxiliary vent punch blade carrying arm. Now, when opening the can 30, as the handle member 11 approaches the rim bead 32 the vent punching blade 42 will intersect the can top 31, and continued downward movement will permit that blade to pierce the can top and descend downwardly thereinto until the under surface of the arm 38 contacts the rim bead 32 and thereby stops further movement of the can opener 10.

If a substantially smaller or considerably larger can is to be opened by the can opener 10, then the arm 39 carrying the auxiliary vent punching blade 43 will come into play. For a shorter diameter can, the member 35 may be rotated 180 degrees from the position shown therefor in Figures 1 and 4, while for larger cans, the auxiliary vent punch carrying and stop member 35 may be left in the position shown. Then, as the handle or body member 11 descends to approach the can top the vent punching blade 43 will intersect the can top and punch an auxiliary vent aperture or orifice therein. The motion of the can opener will then be stopped by the shoulders 44-44 which provide convenient stop means, and in the case of larger cans, stop the motion of the can opener prior to any contact with the can top by the vent punching blade 42 on the shorter arm 38.

42 on the shorter arm 38.

From the foregoing, it will be readily observed that by the principles of the present invention I have provided a very economical and convenient and efficient can opening means operable to, first, equalize the pressure in the can with the outside atmosphere, second, cut a principal can opening aperture in the can, and, third, cut an air inlet aperture in the can substantially diametrically opposite to the principal can opening aperture.

It will be readily observed that numerous variations and modifications and different embodiments of the present invention may be developed and constructed without departing from the true spirit and scope of the novel concepts and principles of my invention. One such modification forming another preferred embodiment of my invention is illustrated isometrically in Figure 5 wherein a can opener 40' is shown with a handle or body member 41' formed from a substantially rigid preferably punchable or stampable material such as heavy gauge sheet metal or the like. At one end of the handle or

body member 41' a principal can opening blade 42' is formed thereon as by punching or stamping or the like, to have a substantially spherically triangular configuration terminating in a cutting edge apex 43' on the under or concave surface 44'. The sides 45' of the cutting blade 44' preferably taper toward the outer convex surface of the blade 42' thereby to provide cutting edges 46 and 47 on the under concave surface 44'. An effervescence or pressure equalizing punch blade 48 which is preferably substantially the same as blade 13 of the can opener 10 is formed to extend from a concave surface 44 and is preferably disposed with respect to the blade 42' in the manner described for the blade 13 with respect to the blade 12 of the can opener 10 whereby the aperture cut in the can top by the blade 48 will be shielded by the concave surface 44' of the blade 42'.

In addition, a fulcrum or bead engaging pivot member 49 is punched from the blade and handle of the can opener 40' on a face thereof corresponding to the face from which the effervescence punch 48 extends and is adapted and arranged to engage the rim bead of the can to be opened and thus to provide a pivot for the can opener 40'. It will also be observed that the fulcrum or pivot rim bead engaging member 49 and the vent punch blade 48 may be punched out in a single operation thus providing the punch blade 48 with a substantially triangular head and providing the fulcrum member 49 with a forked or tined appearance.

Since numerous other modifications and variations may be made without departing from the scope and spirit of the novel concepts of the principles of my invention, I intend to cover all such modifications and variations as fall within the true spirit and scope of the novel concepts and the principles of my invention.

I claim as my invention:

35 A can opener operable to pierce an effervescence vent in a can cover prior to cutting a principal aperture in the can cover and to shield the vent with the blade for cutting the principal aperture prior to cutting the principal aperture, comprising an elongated body member of substantially rigid material, an end of said body member formed as a cutting blade and disposed at an angle to the remainder of the member, a can bead engaging fulcrum member formed integrally with said body as a portion thereof and projecting from a side of said body member 40 with its free end disposed as the vertex of said angle, and a vent piercing blade formed integrally with said body as a portion thereof and projecting from the same side of said cutting blade, said fulcrum member and said piercing blade being formed from a single punching and having 45 conjointly punched ends whereby the piercing blade has a pointed end and the fulcrum member has a forked end.
